J. L. D. BLEVANS

BOOT AND LINER FOR AUTOMOBILE AND SIMILAR CASINGS

Filed Nov. 30, 1920

INVENTOR
By James L. D. Blevans

ATTORNEY

UNITED STATES PATENT OFFICE.

JAMES L. D. BLEVANS, OF DALLAS, TEXAS.

BOOT AND LINER FOR AUTOMOBILE AND SIMILAR CASINGS.

Application filed November 30, 1920. Serial No. 427,447.

To all whom it may concern:

Be it known that I, JAMES L. D. BLEVANS, a citizen of the United States, residing at Dallas, in the county of Dallas and State 5 of Texas, have invented new and useful Improvements in Boots and Liners for Automobile and Similar Casings, of which the following is a specification.

This invention relates to boots or liners 10 for automobile and similar casings.

The object of the invention is to provide a boot which is adapted to be used within the casing and is known as an inside boot in contradistinction to an outside boot which 15 latter goes over the tread and side wall of the casing. Considerable trouble has been had with inside boots due to creeping, slipping and tube pinching. If the inside boot is allowed to move relatively of the casing 20 and tube sufficient friction will be set up to cause the tube to blow out, thus becoming a detriment rather than a help. Inside boots have been made with hooks for engaging the bead of the casing, but in applying the 25 casing these hooks are often displaced and caused to cut the tube and also fail to hold the boot in place.

The object of my invention is to provide an inside boot which is equipped with hooks 30 adapted to engage the bead of the casing in such a manner that they cannot be displaced while in use, or while applying the casing to the rim. A further object is to provide hooks with long shanks so that they may be 35 fastened to the boot a suitable distance inwardly from the edges thereof, whereby said edges may be reduced in thickness, thus causing the boot to better fit between the beads of the casing.

40 A particular object is to so form the hooks that after being engaged with the beads of the casing, said hooks cannot be displaced laterally, thus assuring a permanent positioning of the said boots.

45 Another object is to provide hooks in the nature of clamps, whereby the boot will be retained in place when the casing is removed from the rim.

A construction designed to carry out the 50 invention will be hereinafter described together with other features of the invention.

The invention will be more readily understood from a reading of the following specification and by reference to the accompany-

ing drawings, in which an example of the 55 invention is shown and wherein:

Fig. 1 is a fragmentary view showing a portion of a rim, casing and tube equipped with a boot constructed in accordance with my invention, 60

Fig. 2 is a perspective view of one end portion of said boot,

Fig. 3 is an enlarged cross sectional view thru a rim and tire equipped with said boot, 65

Fig. 4 is a perspective view of one of the hooks.

In the drawings the letter A designates an ordinary tire casing, B a boot constructed in accordance with my invention and H an 70 ordinary inner tube. This boot may be formed of a number of layers of rubberized fabric and suitably shaped. The adjacent edges of the boot are reduced so as to better fit in the casing A and a flap B' is secured 75 to the inside of the boot and lapped over the split between the edges thereof.

Inwardly from the longitudinal edges of the boot and on the outside thereof I secure suitable hooks C by means of rivets I. The 80 hooks have long shanks so that their retaining portions will be below the edges of the boot and the rivets at the top of the hooks are set inwardly some distance from said edges and cannot readily pull out. Each 85 hook is bent at an angle, as is shown in Fig. 4 so as to conform to the cross sectional shape of the bead D of the casing. The bead is provided with a bottom edge or surface E and an outer surface F and the hooks 90 are shaped so that their shank portions rest against the inner side of the bead, while their bottoms engage under the edge E and their lips at their outer ends engage the outer side F of said bead. 95

It will be seen that the boot B fits contiguous to the inner surface of the casing and the hooks snugly engage three sides of the bead of the casing. By this arrangement the boot is held in place and the engagement of the hooks will be so tenacious that a tool will be required to disengage the same from the bead. It will be seen that after the boot has been placed in the casing it cannot be displaced when the casing is inserted in the rim. Also the boot will not 100 creep and, therefore, will reduce friction 105 which is caused by creeping boots. There

will be no cut tube or pinched tube. The boot being on the inside is of great advantage as it will be protected by the casing and will wear very much longer, besides giving 5 a smooth tread to the tire.

Various changes in the size and shape as well as modifications and alterations may be made without departing from the spirit of the appended claim.

10 What I claim, is:

A boot for a tire casing having beads, metal hooks arranged upon the outer faces of the boot near its edges, each hook comprising an inner portion to engage the inner 15 face of the bead, a base carried by the inner

portion engaging the bottom wall of the bead, and an outer flange projecting upwardly from the base to engage the outer face of the bead, said hooks having interlocking engagement with the beads whereby 20 the boot is held securely connected to the beads when the beads are spread during the insertion of the inner tube.

In testimony whereof I have signed my name to this specification in the presence of 25 two subscribing witnesses.

JAMES L. D. BLEVANS.
